COMBINED CONVERTIBLE SOFA AND NIGHT TABLE

Jack Rozett, Levittown, Pa., assignor to Eclipse Sleep Products, Inc., Brooklyn, N.Y., a corporation of New York

Filed June 26, 1969, Ser. No. 17,905

Term of patent 14 years

Int. Cl. D6—01

U.S. Cl. D15—11

FIG. 1

FIG. 3

FIG. 1 is a somewhat isometric view of a combined convertible sofa and night table, showing my new design.

FIG. 2 is a somewhat exploded view of the sofa shown in FIG. 1 with three of the cushions omitted for the sake of clarity.

FIG. 3 is a somewhat isometric view of the sofa of FIG. 1 in the open position.

The side not shown is like the side shown while the back of the article is conventional in appearance.

I claim:

The ornamental design for a combined convertible sofa and night table, substantially as shown and described.
